UNITED STATES PATENT OFFICE.

JOSEPH A. GARDNER AND DAVID S. GARDNER, OF MEMPHIS, TENNESSEE.

DENTAL FLASK.

1,414,566.

Specification of Letters Patent. Patented May 2, 1922.

Application filed March 24, 1921. Serial No. 455,085.

To all whom it may concern:

Be it known that we, JOSEPH A. GARDNER and DAVID S. GARDNER, both citizens of the United States, residing at Memphis, in the 5 county of Shelby and State of Tennessee, have invented certain new and useful Improvements in Dental Flasks, of which the following is a full, clear, and exact description, which will enable others skilled in the 10 art to make and use the same.

This invention relates to improvements in casting appliances, and consists more particularly in improvements in the flask and crucible or ladle holder for holding the 15 investment material, or material of which the mold and melting crucible or ladle are made. It particularly relates to a flask having an integral crucible, or ladle, holder whereby the crucible and mold may be formed in one 20 piece without joint through which the metal might escape in passing from the crucible to the mold.

The improved flask and crucible holder containing the combined mold and crucible 25 constructed as hereinafter set forth is especially designed for use in a centrifugal casting machine in which machines the mold and crucible are placed on an arm adapted to revolve about a pivot, the crucible being 30 placed nearer the pivot and the material contained therein being thrown by centrifugal force from the crucible into the mold. The means for, and method of forming, the mold and crucible in the said flask and ladle holder 35 are fully described and shown in our Patent No. 1,195,802 issued August 22nd, 1916, to which reference is made.

The objects of the present invention are to provide first; an integral flask and crucible 40 holder whereby the mold and crucible may be made in one piece especially for forming dental, jewelers, or other small castings more particularly of precious metals in which it is essential that even the smallest loss of the 45 precious metal be prevented; to provide, second; a flask for the mold which may be adjusted to the size of the casting to be made, thus reducing the amount of investment material used, but more especially reducing the 50 amount of such material which must be heated in melting out the wax pattern used in forming the mold and in preparing the mold; and to provide, third; means whereby the flask and crucible holder may be quickly

and securely attached to the arm of the centrifugal machine, this being a very essential point in a ladle involving small quantities of highly heated and valuable metals.

With these objects in view, the invention consists in the novel details of construction 60 and combination of parts more fully herein-after disclosed in the drawings, specifications, and claims.

In the drawings:

Fig. 1 is a perspective view of the improved flask and crucible holder;

Fig. 2 is a plan view of the same showing the crucible as formed therein.

Fig. 3 is a section on the center line, showing the flask and crucible holder with the 70 crucible and mold therein also in section.

Fig. 4 is a perspective view of a modified shape of the device.

Referring now to the drawings in which the various parts are indicated by the same numerals in all the views, 1 is the crucible holder, 2 is the flask integral with the crucible holder, which flask and crucible holder are formed preferably by taking a tube of thin metal of the length of the combined 80 crucible holder and flask and cutting away approximately one half of the same for the length of the crucible holder. 3, is a lug or extension from the lower edge of the crucible holder 1 by means of which the 85 same may be quickly clamped or secured to the arm of the centrifugal machine. It will be noted that both ends of the flask are open and that the end of the crucible is open, but that it may be closed either partly or wholly 90 if desired. 4 is an extension member for the flask 2 which in the preferred form is a metal tube adapted to fit over the flask 2 and to slide in or out thereon to adjust the length of the flask. 5 is a clamping screw, being a 95 means to fasten the extension in the desired position. 6 is the crucible formed in the investment material 7, 8 is a mold also formed therein and 9 a channel or sprue leading from the crucible to the mold. The crucible 100 is made by means of a solid pattern of metal, wood, or other material shaped to the desired form of the crucible 6. In one end of the pattern, a pin is placed to form the sprue 9 and on the end of this pin a wax pattern of 105 the desired casting is placed to form the mold 8. If the wax pattern is small, the extension 4 is brought even with the end of the

flask 2, if longer as shown the extension 4 is brought out until sufficiently beyond the pattern and is then clamped in place by means of the set screw 5. Ordinarily in filling the 5 flask and crucible holder the extension end 4 is placed at the top and the flask and crucible filled from that end, a suitable holder being used to hold the patterns and flask during the filling with investment or mold material. 10 When the investment material has set or hardened, the crucible pattern is removed and the pin withdrawn from the sprue 9. The wax pattern is then removed by heating, and the flask and crucible holder containing 15 the combined crucible and mold is then placed on the arm of the casting machine and attached thereto, the precious metal is placed in the crucible 6 and heated by the application of a blowpipe or other intense 20 flame and when the metal has been reduced to a molten condition, the machine is set in motion and the metal thrown by centrifugal force into the mold.

It will readily be seen that the amount of 25 investment material that must be heated in removing the wax mold and that must be kept hot when reducing the metal is an important factor in quick and economical work and that an important and valuable result 30 has been accomplished in furnishing the adjusting means whereby the amount of material needed can be properly and easily regulated. It will also be noted that it is advantageous to melt out the wax pattern before placing the mold and crucible holder on the casting machine and that the lug for attaching the same is of great importance 35 because of the quickness with which the flask may be attached, and the security attained in holding the same.

This invention has been described as a 40 tubular flask and such form is the simplest to make and the easiest for which to secure material. It will however, be readily seen 45 that there is little of inherent advantage in such a shape and it is distinctly to be understood that the cross section of the crucible holder, the flask, and the extension may be rectangular, oval or such other shape as may 50 be most satisfactory. It will also be distinctly understood that the extension 4 may telescope within instead of outside the flask and that the clamping means shown is typical only, and may be varied from the form 55 shown. A flask, 2^a, ladle, 1^a, and extension, 4^a, of rectangular cross section is shown in Fig. 4.

Having now fully described our invention,

what we claim and desire to secure by Letters Patent of the United States is:—

1. A casting appliance comprising an open top crucible holder, an enclosed flask with open ends integral therewith, an extension for the said flask open at both ends and means of clamping the said extension. 60

2. A casting appliance comprising an open top crucible holder, an enclosed flask with open ends integral therewith, an extension for the said flask, open at both ends, means for clamping the said extension in any desired position relative to the said flask and a lug extending from the bottom of the said ladle holder. 70

3. A casting appliance having a crucible holder with a bottom and sides, a flask having sides and bottom integral with the sides and bottom of the said crucible holder, and a top, and an extension having top, sides and bottom corresponding with the top, sides, and bottom of the said flask and adapted to 80 increase the length thereof, and means for clamping the said extension in any desired position on the said flask. 75

4. A casting appliance comprising a semi-cylindrical crucible holder, an integral cylindrical flask, a slidably mounted cylindrical extension, means for clamping the said extension in any desired position and an integral crucible and mold formed in the said crucible holder, flask and extension. 85

5. A casting appliance comprising a semi-cylindrical crucible holder, an integral cylindrical flask, a slidably mounted cylindrical extension, a screw for clamping the said extension in any desired position, and an integral crucible and mold formed in the said crucible holder, flask and extension. 90

6. A casting appliance having a crucible holder with a bottom and sides, a flask having sides and bottom, integral with the sides and bottom of the said crucible holder, and a top, an extension having a top, sides and a bottom coordinating with the top, sides and bottom of the said flask and adapted to increase the length thereof, means for clamping the said extension in any desired position on the said flask, and an integral crucible and mold formed in the said crucible holder, flask and extension. 100

In testimony whereof we have hereunto set our names.

JOSEPH A. GARDNER.
DAVID S. GARDNER.
